ROCHUS MAX ZU LYNAR PASSY-DE CHIMANG, OF NEW YORK, N. Y., ASSIGNOR TO
MAR-DE-PASSY CORPORATION, OF NEW YORK, N. Y., A CORPORATION OF NEW
YORK.

MARINE VESSEL.

Refiled for abandoned application Serial No. 645,324, filed June 14, 1923. This application filed December 10, 1925. Serial No. 74,613.

The present invention relates to improvements in marine-vessels or ships, more particularly to the construction of the hulls thereof.

5 One of the objects of the invention is to so construct the forebody of the hull of the vessel that it is adapted to cleave the water as it advances and at the same time leave, as far as possible, undisturbed the water 10 over which its midship portion has to pass.

Another object of the invention is to so shape the hull that the amount of its submerged surface, or in other words its draft is reduced to a possible minimum, where- 15 by its speed is increased.

A further object of the invention is to provide the hull with compartments or bulkheads which serve at the same time as ballasting devices, designed to steady and trim 20 the vessel, and also to prevent careening, rolling, pitching, etc.

A still further object of the invention is to so shape the bottom of the vessel that the propellers and rudder thereof receive at all 25 times a free and solid flow of water for their efficient operation.

With these and other objects in view, which will more fully appear as the nature of the invention is better understood, the 30 same consists in the combination, arrangement and construction of parts hereinafter described, pointed out in the appended claims and illustrated in the accompanying drawings, it being understood that many 35 changes may be made in the size and proportion of the several parts and details of construction within the scope of the appended claims, without departing from the spirit or sacrificing any of the advantages 40 of the invention.

One of the many possible embodiments of the invention is illustrated in the accompanying drawings, in which:—

Figure 1 is a sheer plan of a hull constructed in accordance with the present invention; Fig. 2 is a bottom plan view thereof; Figs. 3 to 10, inclusive, are sections taken on Fig. 1, each section being taken on a line thereof which is indicated by numerals of 45 reference corresponding to the numeral of its respective figure; and Fig. 11 is a body plan of the hull.

The bow 12 of the hull has a sharp cutwater 13, the sides 14 of the bow, more par-

ticularly the freeboard region thereof, expanding along fine lines to produce the greatest width of beam 15 in the forebody of the vessel. From this point the sides converge along gentle stream lines toward the stern 16, which is rounded as shown in Fig. 2 of the drawings. The midship body 17 of the hull, extending from the plane indicated by the section line 5—5 to approximately the plane indicated by the section line 9—9, indicated in Fig. 1 of the drawings, has substantially vertical sides 18 and a flat bottom 19. At or about the plane indicated by the section line 9—9 in Fig. 1 of the drawings, the bottom rises gradually toward the stern and is gradually curved transversely, 70 see for instance Fig. 10 of the drawings.

In the forebody the bottom is constructed as a downwardly directed wedge, the apex of which appears most prominent at 20. This apex is gradually drawn up or flattened out as it passes aft, as shown in Figs. 3 and 4, and at or about the plane 5—5 merges into a flattened portion 21 (Fig. 5), which is disposed a substantial distance below the bottom portion 19 of the hull proper. The flattened portion 21 rises from forward 75 aft and merges into the flattened bottom 19 in the plane 9—9. The flattened portion 21 forms the bottom of a bulkhead structure 22, which surrounds the flat bottom of the hull and part of the sides thereof in the midship body of the hull and for some distance in the forebody, the width of the bulkhead bottom expanding gradually along fine lines from the section line 4—4 to amidship and thence gradually decreasing to the plane indicated by the section line 9—9. The greatest width of the bulkhead bottom exceeds considerably that of the greatest width 80 of beam, as clearly shown in Fig. 2 of the drawings. The bulkhead structure may be divided transversely into a plurality of water-tight compartments which may be used as coal bunkers and for other storage purposes, and also engine rooms. The sides 100 of the bulkhead structure, denoted by the numeral 23, are curved outwards from the sides 18 of the hull and then downwards, as shown at 24, joining the bottom of the bulkhead structure.

The bottom of the bulkhead structure is flat in the plane 5—5, as indicated above, and thence longitudinally recessed, flattening

out gradually until it joins the stern at the plane 9—9. The depth of the recess decreases thus gradually, as it proceeds aft.

The hull is provided with two propellers 5 25, the shafts 26 of which are driven by engines disposed in the bulkhead structure. These propellers are located below the rising bottom portion of the hull in the after-body and in line with the longitudinal recess 10 in the bottom portion of the bulkhead structure, thereby receiving continuously a free and solid flow of water for their efficient operation. Inasmuch as these propellers are disposed a considerable distance forward 15 of the stern of the vessel, they will be fully submerged under all conditions of lading and in all kinds of weather.

It will be observed that the forward wedge-shaped portion of the vessel is comparatively slender, thereby producing a reduced bow wave, which is thrown further aft than usual, and dividing the water so that the ship tends to go through without rising. Coming to the midship portion, the 25 water divided by the wedge passes, guided by the sides 23 of the bulkhead structure, to either side, and comparatively undisturbed water is left, over which the recessed bottom of the bulkhead structure can glide. The bulkhead structure, by reason of its 30 width compared with that of the hull proper, serves as a ballasting device projecting from the vessel sides laterally, thereby forming a resistance surface to prevent careening or 35 capsizing and also to enable the vessel to point or sail closer to the wind and to prevent making leeway. The bulkhead structure, at the same time, prevents rolling and

pitching in addition to its normal function, that is to say in addition to its providing 40 water-tight compartments. Furthermore, the bulkhead structure, by reason of its width, decreases considerably the draft of the vessel, thus effectively increasing its speed when moving through the water. 45

Inasmuch as the bottom of the bulkhead structure rises gradually from its point of commencement as it passes aft, the vessel has no tendency to rise at the bow. Pitching is thus to a great extent prevented. 50

What I claim is:

1. A marine vessel comprising a hull, and a longitudinal laterally extending exterior bulkhead structure thereon surrounding the bottom and part of the sides of said hull, 55 said bulkhead structure having a bottom rising from its bow end to its stern end, said bottom being shaped to provide a longitudinal and inwardly extending recess.

2. In a marine vessel according to claim 1, 60 the bottom of said bulkhead structure merging into the bottom region of the bow portion and the bottom region of the stern portion of said hull.

3. In a marine vessel according to claim 1, 65 the bottom of said hull being substantially flat throughout the midship body.

4. In a marine vessel according to claim 1, 70 said bulkhead structure extending over part of the bow portion and the midship body of said hull.

Signed at New York, in the county of New York, and State of New York, this 9th day of December, A. D. 1925.

ROCHUS MAX zu LYNAR PASSY-de CHIMANG.
